UNITED STATES PATENT OFFICE.

GEORGE MORBY, OF ROBINSON, UTAH.

SMOKE-PURIFIER.

Specification of Letters Patent.

Patented March 3, 1908.

No. 830,747.

Application filed March 29, 1907. Serial No. 365,326.

To all whom it may concern:

Be it known that I, GEORGE MORBY, a subject of the King of Great Britain, residing at Robinson, in the county of Juab and State of Utah, have invented new and useful Improvements in Smoke-Purifiers, of which the following is a specification.

My invention relates to apparatus for treating and purifying smoke and more particularly smoke from smelting furnaces.

As is well known the smoke and fumes given off from smelting furnaces often contain sulfurous and other obnoxious gases, which if allowed to escape into the air have an injurious effect upon surrounding vegetation. Mineral matter in suspension is often carried over with the products of combustion from smelting furnaces and it is often desirable to condense and collect such vaporized or finely divided material.

It is the object of my invention to provide apparatus for use in connection with smelting furnaces and the like by the use of which it will be possible to precipitate and collect any mineral matter which may be carried over with the products of combustion into the smoke flue and also to rid escaping gases of their poisonous and harmful ingredients such as sulfur dioxid etc.

With the above objects in view my invention consists in the arrangement and construction hereinafter described and shown in the accompanying drawings, in which—

Figure 1 is a side elevation of my complete apparatus. Fig. 2 is a sectional view of a fragment of the flue, and, Fig. 3 is a vertical central section on an enlarged scale through the smoke receiver and associated parts.

Referring to the drawings in detail, 1 represents a flue constructed preferably of rectangular section and of sheet metal and supported on foundations 2 in a slightly inclined position. Connected with the upper end of this flue is a pipe 5 for supplying water thereto, and at the opposite end is a water discharge spout 4 (see Fig. 3). The flue 1 is surmounted at its upper end by a stack 6 of usual construction. At its lower end the flue 1 connects with the receiver 8 and from the receiver 8 extends a flue 7 by which products of combustion enter the apparatus. Below the receiver 8 and arranged under the discharge spout 4 is disposed a settling tank 9 from which leads a waste pipe 10. The flue 1 is provided in its sides with suitable doors

11 by which access may be had to the interior thereof and with air supply pipes 12. As clearly shown in Fig. 2 these pipes 12 are on the inside of the flue inclined towards the stack. Within the stack 6 is arranged a steam jet 13 for the purpose of creating a draft as is well known and which may be supplied with steam from any suitable boiler (not shown) or from engine exhausts. Above the flue 1, carried on supports 18 resting on the base 19 is a tank 3 of large capacity and depending from the bottom thereof is a plurality of pipes 14 provided with valves 15. Disposed within the upper part of the flue and extending transversely thereof is a plurality of sprayers 16 which connect with the pipe 14. These sprayers are perforated on their lower sides and are closed at their ends by means of removable plugs 17 which extend through the walls of the flue. At the point where the flue 1 enters the receiver 8 is arranged a sliding gate or valve 20 carried by a cord 21 passing over pulleys 22, supported on brackets 30 extending from the top of the receiver. To the other end of the cord 21 is attached a counter-weight 23.

Extending upwardly from the top of the receiver is an auxiliary stack 24 having its bottom closed by means of a damper 27 lined with fire-brick 28 and controlled as to its position by a lever 25 pivoted to the outside of the receiver as at 26. When the gate 20 is lowered so that its lower end fits in the groove 29 the opening 31 is closed thereby cutting off communication between the receiver and the flue.

The operation of my improved apparatus is as follows: The products of combustion are conducted by means of the flue 7 from the furnace and enter the receiver 8 whence they pass through the opening 31 into the flue 1. As they pass through the flue they are met by showers of water delivered from the tank 3 through the sprayers 16 and by air blasts through the pipes 12. These air blasts tend to promote a more perfect combustion and the water spray tends to absorb and condense the sulfurous or other mineral matters contained in the waste gases. At the same time a stream of water is admitted from the pipe 5 and flows downwardly along the bottom of the flue carrying away any deposits or precipitates and discharging them through the spout 4 into the settling tank 9.

I have found that in some cases it is ad-

vantageous to use salt water in the tank 3, but I desire it understood that I do not wish to limit myself in this particular as either salt water, fresh water or other suitable liquid may be employed in the tank 3 as desired. I wish it to be further understood that I do not limit myself to the use of the tank 3 since water or other suitable liquid may be supplied directly from pumps or other suitable source.

When it is desired to clean or repair the flue or stack 6 the gate 20 is lowered thus shutting off communication with the receiver 8 and, the damper 27 being opened, the products of combustion escape directly through the auxiliary stack 24.

It will thus be seen that I have provided an apparatus which is very simple and efficient, which contains no tortuous or inaccessible passages liable to become clogged and which can be readily attached to any ordinary furnace, and it is thought the numerous advantages of my construction will be readily appreciated by those skilled in the art.

What I claim is—

1. In an apparatus for treating products of combustion from furnaces, a receiver into which said flue empties, a stack extending from said receiver, a second flue also extending from said receiver, and a second stack connected with said last-named flue.

2. In an apparatus for treating products of combustion from furnaces, an inclined flue, means for admitting a liquid in the form of spray at a plurality of points in said flue, and means for admitting air also at a plurality of points.

3. In an apparatus for treating products of combustion from furnaces, an inclined flue, means for supplying said products of combustion to the lower end thereof, a stack communicating with the upper end thereof, a plurality of air blasts extending through

the side of said flue and directed toward said stack, and means for supplying water to the interior of said flue.

4. In an apparatus for treating products of combustion from furnaces, a flue through which said products pass, said flue being substantially straight and of rectangular cross section, and doors arranged in the side of said flue whereby ready access may be had to all parts of the interior of said flue.

5. In an apparatus for treating the products of combustion from furnaces, an inclined flue, a stack at the upper end thereof, means for supplying a constant stream of water to the upper end of said flue, and additional means for supplying a transverse spray of suitable liquid at a plurality of points in said flue.

6. In an apparatus for treating products of combustion from furnaces, an inclined flue, a plurality of transversely-disposed spray heads therein through which a suitable liquid may be supplied, a pipe for supplying a constant flow of water to the upper end of said flue, and a discharge spout connected with the lower end thereof and overhanging a settling tank, whereby the material precipitated by said spray may be carried by the water into the settling tank.

7. In combination, a flue extending from a furnace, a receiver into which said flue delivers, an inclined flue extending from the opposite side of said receiver and provided with suitable spraying means on the interior thereof, a discharge spout opening from said inclined flue into said receiver, and a settling tank adjacent said receiver and arranged to receive the discharge from said spout.

In testimony whereof, I affix my signature in presence of two witnesses.

GEORGE MORBY.
